UNITED STATES PATENT OFFICE

2,607,316

INDICATOR FOR COOKING RANGES

Charles M. Mayer, Mansfield, Ohio, assignor to
The Tappan Stove Company, Mansfield, Ohio,
a corporation of Ohio

Original application April 13, 1948, Serial No.
20,678. Divided and this application July 1,
1949, Serial No. 102,532

2 Claims. (Cl. 116—129)

1

This invention relates to an indicating mechanism for use on cooking ranges, by which one can tell at a glance whether or not a burner or heating element is operating and whether it is set for low, medium or high heat. This application is a division of my co-pending application Serial Number 20,678 filed April 13, 1948, upon which application Patent No. 2,494,892 was issued on January 17, 1950.

The invention comprises a pair of discs which are disposed in axial alignment with each other within a stationary ring which is secured to and extends outwardly from the front of a cooking range. The valve stem by which a burner is controlled projects out through aligned axial apertures in the discs and has an operating handle removably secured to the outer end thereof adjacent the outermost disc. One of the discs is secured to the stationary ring and the other ring is secured to the valve stem for rotation therewith. One of the discs is opaque and has a window therein; and the other disc has a translucent portion with indicia thereon for showing whether a burner is set for low, medium or high heat. A small electric bulb is mounted behind the pair of discs in position to project light through the translucent portion of one of the discs and through the window of the other disc when the bulb is energized. The energization of the bulb is controlled by a suitable switch which is opened and closed by the valve stem. The relative position of the window and the translucent portion with respect to each other indicates the setting of the burner. The invention is shown and described herein as applied to a gas range, but it will be obvious that it can be applied to an electric range equally well.

The principal object of the invention is to provide a simple efficient and ornamental mechanism for indicating the setting of a cooking range burner.

Other and more limited objects of the invention will be apparent from the following specification and the accompanying drawings forming a part thereof wherein:

Fig. 1 is a front elevation of a gas cooking range having my invention applied thereto;

Fig. 2 is an enlarged horizontal section taken on the line 2—2 of Fig. 1;

Fig. 3 is a vertical section taken on the line 3—3 of Fig. 2;

Fig. 4 is a vertical section taken on the line 4—4 of Fig. 2;

Fig. 5 is an enlarged front elevation of one of the indicators shown in Fig. 1;

Fig. 6 is a vertical section taken on the line 6—6 of Fig. 3;

2

Fig. 7 is a view similar to Fig. 3 showing a slightly modified form of my invention;

Fig. 8 is a front elevation of the indicator shown in Fig. 7; and

Fig. 9 is a vertical section taken on the line 9—9 of Fig. 7.

Referring now to the drawings by reference characters, the numeral 1 indicates generally a gas cooking range of the divided top type wherein a pair of burners 2 are mounted one behind the other adjacent each side of the range. The burners 2 are located in top burner compartments 3 and have suitable utensil-supporting grates 4 disposed over them. The top 5 of the range has a splash back 6 extending upwardly from the rear edge thereof. Beneath each of the burner compartments 3 is a storage compartment which is closed by a door 7. Between the storage compartments is an oven and a broiler which are closed by doors 8 and 9 respectively. The numerals 10 and 11 indicate handles by which the doors 8 and 9 are opened and closed. An escutcheon plate 12 is removably secured to the front wall 13 of each of the burner compartments 3 above the door 7.

Gas is supplied to the burners 2 from a common manifold 14 through valves 15 which control the operation of the burners, there being provided a separate valve for each burner. The valves 15 are secured to the manifold 14 which is held in place by suitable means, not shown. Each valve 15 has an operating stem 16 which extends forwardly from its valve through an opening 17 in the wall 13 and an enlarged opening 18 in the escutcheon plate 12. The outer end of each valve stem 16 has a flattened portion 19 and is slotted as indicated at 20. An operating handle 21, by which a valve stem 16 is rotated to open and close a valve 15, is frictionally secured to the outer end of each valve stem 16, so that it can be readily removed and replaced as desired. The flattened portions 19 of the valve stem 16 which cooperate with complementary flattened portions in sockets 22 of the handles 21 assure the rotation of the valve stems when the handles 21 are turned. The slots 20 enable the valve stem 16 to frictionally engage the walls of the sockets 22 with sufficient force to retain the handles in place upon the valve stem during normal operation. The handles 21 are molded from suitable opaque plastic material and are preferably shaped as shown, but can be shaped otherwise if desired.

A cylindrical ring 30, having the outer end thereof closed by a disc 31 which is rigidly secured in place, is disposed about the opening 18 in the escutcheon plate 12. The valve stem 16

extends out through a central aperture 32 in the disc 31; and the ring 30 is held against outward movement by the handle 21 which bears against the outer face of the disc 31. The ring 30 is held against lateral movement by a pair of tongues 35 which engage in slots 36 extending out from the opening 18 in the escutcheon plate 12. The lower half 37 of the disc 31 is opaque and the upper half is translucent and is divided into three sections 38, 39 and 40 which are preferably of different contrasting colors. As shown in Fig. 5 the sections 38, 39 and 40 may have indicia thereon to indicate whether the burner is set for low, medium or high heat. In the absence of indicia the contrasting color of the sections 38, 39 and 40 will indicate the setting of the burner as will be described. An opaque disc 41 having a window 42 therein is secured to the valve stem 16 for rotation therewith by a set screw 43. The disc 41 is disposed directly behind the disc 31 within the ring 30.

A casing 45, in which is mounted a small electric bulb 46 and a switch 47, is associated with each opening 18 in position for the bulb 46 to project light out through the opening 18 against the back of the disc 41. The valve stems 16 extend through the casing 45 and are adapted to open and close the switches 47 when they are turned. When the valves 15 are closed the flattened portions 19 of the valve stems 16 lie parallel to and closely adjacent the upper ends of buttons 48, and when the valve stems are rotated to open the valves 15, the rounded sections of the stems cam the buttons 48 downwardly closing the switches 47 and energizing the bulbs 46. As a valve stem 16 is turned to open a valve 15 the window 42 in the disc 41 is brought successively behind the translucent sections 38, 39 and 40 of the disc 31. Light from the bulb 46 will then shine through the window 42 and illuminate the translucent section behind which it happens to be located and thus indicate whether the burner is operating at low, medium or high flame.

In Figs. 7, 8 and 9 I have shown a slightly modified form of my invention. This form of the invention is very similar to the form shown in Figs. 1 to 6, the various parts of the two forms being substantially the same, but arranged somewhat differently with respect to each other. In this form the disc 41 is secured to the ring 30 and the disc 31 is rigidly secured to the valve stem 16 directly behind the disc 41. The window 42 is preferably disposed above the valve stem 16 as shown in Figs. 7 and 8, but it may be located differently if desired. As the valve stem 16 is turned to open the valve 15, the bulb 46 is energized and the translucent sections 38, 39 and 40 of the disc 31 are successively brought up behind the window 42. Light from the bulb 46 will shine first through the translucent section and then out through the window 42, giving a visual indication of how the burner is operating.

When the invention is used with an electric range the stems 16 operate suitable switches which control the operation of the heating elements.

From the foregoing it will be apparent that I have provided a very simple, effective and ornamental mechanism for accomplishing the objects of my invention.

It is to be understood that I am not restricted to the specific construction shown and described herein as various modifications may be made thereto within the scope of the appended claims.

What is claimed is:

1. In a device of the character described the combination of a gaseous fuel burner operatively mounted in a cooking range, a valve by which the supply of fuel to said burner is selectively controlled disposed behind the front wall of said range, a valve operating stem extending out through an enlarged aperture in the front wall of said range, an operating handle removably secured to the outer end of said stem, a ring of opaque material removably but non-rotatably secured to the front wall of said range between the said front wall and said operating handle and surrounding said aperture, a first disc and a second disc, both of said discs being disposed closely adjacent to each other within said ring about said operating stem, said first disc being rigidly secured to said ring and having at least a portion thereof formed of translucent material with indicia thereon for indicating different heating conditions of said burner, said second disc being formed of opaque material and rigidly secured to said operating stem for rotation therewith behind said first disc, a window in said second disc, and an electric light bulb mounted behind said enlarged aperture and operative when energized to project light through said window and then through said translucent portion and render the indicia in front of said window clearly visible.

2. In a device of the character described the combination of a heating element operatively mounted in a cooking range, a rotatable stem by which operation of said heating element is controlled extending out through an enlarged aperture in the front wall of said range, an operating handle removably secured to the outer end of said stem, a ring of opaque material removably but non-rotatably secured to the front wall of said range between the said front wall and said operating handle and surrounding said aperture, a first disc and a second disc, both of said discs being disposed closely adjacent to each other within said ring about said operating stem, said first disc being rigidly secured to said ring and having at least a portion thereof formed of translucent material with indicia thereon for indicating different heating conditions of said heating element, said second disc being formed of opaque material and rigidly secured to said operating stem for rotation therewith behind said first disc, a window in said second disc, and an electric light bulb mounted behind said enlarged aperture and operative when energized to project light through said window and then through said translucent portion and render the indicia in front of said window clearly visible.

CHARLES M. MAYER.
